SCORER CONSOLE OR THE LIKE

George E. Schaefer, Muskegon, Mich., and Richard G. Reineman, Balboa, Calif., assignors to Brunswick Corporation, Chicago, Ill., a corporation of Delaware

Filed Feb. 3, 1967, Ser. No. 5,676

Term of patent 14 years

(Cl. D34—5)

FIG. 1 is a front perspective view of a scorer console or the like embodying our new design;

FIG. 2 is a side elevational view thereof taken from the same side as that seen in FIG. 1;

FIG. 3 is a rear perspective view thereof, also illustrating the other side;

FIG. 4 is a top plan view thereof.

The dominant features of the generic design, i.e. the overall shape of the scorer console or the like, are shown in full lines on the drawings, while the broken lines in FIG. 1 (also visible in FIGS. 2 and 3) illustrate optional ornamentation. The broken lines in FIG. 4 (also visible in FIG. 3) illustrate environmental printers.

We claim:

The ornamental design for a scorer console or the like, as shown and described.
